UNITED STATES PATENT OFFICE

TROY R. LIVINGSTON, OF MUNCIE, INDIANA, ASSIGNOR, BY MESNE ASSIGNMENTS,
TO THE DELPHOS BENDING COMPANY, OF DELPHOS, OHIO, A CORPORATION OF
OHIO

DRY-WOOD-BENDING MACHINE

Application filed September 8, 1928. Serial No. 304,667.

My invention relates to machines for bending wood in the dry state.

My present invention is a development of the general type of dry-wood bending machine shown in Patents Nos. 960,525 and 1,507,368, granted to Charles W. Elliott on June 7, 1910, and September 2, 1924, respectively.

It has for its object the prevention of the dissipation of the heat in the bending roll, so that such heat may be more effectively, uniformly, and accurately applied to the wood to be bent; and also the automatic control of such heat, to increase still further the uniformity of the heating action on the wood being bent.

In carrying out my invention, I provide in connection with a main bending roll which is heated, and which acts on one side of the wood to be bent, and with other rolls and rollers and usually a flexible plate which act on the other side of such wood, to produce bending of the wood as it is fed through the machine, a hood over the main or heated roll to retain the heat in such bending roll. In addition, I provide a thermostatically operated valve which controls the supply of gas used for heating the main bending roll, and which is operated by a thermostat responsive to the temperature developed in the machine. Such thermostat is desirably located in the hood above referred to, in fairly close proximity to the main bending roll.

The accompanying drawing illustrates my invention. Fig. 1 is a transverse vertical section, substantially on the line 1—1 of Fig. 2, of a dry-wood bending machine embodying my invention; Fig. 2 is a front elevation, with some parts broken away, of the dry-wood bending machine shown in Fig. 1; Fig. 3 is a plan of the same machine; and Fig. 4 is an enlarged section through the thermostatically operated valve.

The frame 10 carries the main bending roll 11, and two supplemental rolls 12 and 13. The three rolls are suitably carried by the frame 10 for rotation on parallel axes. The main roll 11 is the heated roll, and is above the level of the other two rolls; and is vertically adjustable by adjusting screws 14.

Strips of wood 15 may be fed into the machine from the left (Fig. 1), and are bent as they pass between the rolls and out at the right-hand side (Fig. 1) of the machine. To obtain this feeding, one of the rolls, and desirably the main or heated roll 11, is suitably driven, as by gearing including a gear 16 fixed to one end of such main roll. The main or heated roll 11 forms the inner concave side of the bent wood strips, while the rolls 12 and 13 co-operate with the sides of the wood strips which are to be the outer or convex sides after the bending. A flexible sheet 17, of sheet metal, usually lies between the rolls 12 and 13 and the strip of wood 15, to bear against that face of the wood which is to be stretched in the bending. Desirably one or more rollers or bars 18 bear against this flexible metal sheet 17 between the two rolls 12 and 13, to support such sheet and the wood strips at about the place where the bending starts; these rollers 18 being supported in a manner which is not here shown because it is not essential to the present invention, although it is conveniently substantially of the general character shown in the aforesaid Elliott Patent No. 1,507,368.

The main roll 11 is hollow; and is open at least one end through spaces between its supporting spokes 20, to provide flue-outlets for products of combustion. Such products of combustion are from the flames, most conveniently gas flames, from a burner 21 which is located within the hollow roll 11. Such burner 21 is in the form of a horizontal tube or pipe, with jet openings for the flames at or near its upper side; and is stationarily supported within the roll 11 so that the flames from it play on the inside surface of the roll 11, desirably on the descending side of the roller. The burner is supported from a stationary hollow rod 22 located on the axis of the main roll 11 and suitably mounted in the frame 10 to serve as the bearing support for the roll 11. Gas from a supply pipe 23 is supplied through an air mixer 24 to the rod or pipe 22, and thus to supply the burner 21.

The construction so far described is not new, so far as the invention of the present application is concerned.

According to the present invention, I provide over the main bending roll 11 a sheet-metal hood 25. This sheet-metal hood is spaced from the roll, but is carried by castings 26 which desirably rest against the surface of the roll 11 and rub thereon. There is such a casting 26 at each end of the roll 11, and desirably one or more intermediate castings, the number depending on the length of the roll and being sufficient to give firm support to the hood. The castings 26 are mainly on the inner side of the hood; but they have extensions 27 which project through to the outside of the hood and are there provided with eyes through which a positioning rod 28 extends.

The hood 25 extends over and around the upper part of the main roll 11, into fairly close proximity to the wood strips; and thus forms a fairly tight hood or enclosure over the upper half of the main roll 11, to hold in the heat of such roll so that there will be little loss of heat from cooling of the roll by radiation and convection, and thus so that the heat may be more effectively, economically, and uniformly applied to the wood 15.

In order to make for still greater uniformity of heat application, and therefore for greater accuracy, uniformity, and permanency of bending of the wood without danger of overheating it, I control the supply of gas to the burner 21 automatically in response to the temperature developed within the roll 11. The use of the hood 25 makes this control readily practicable.

To obtain this control, I provide in the pipe 23 a valve 30, which is spring-pressed towards its seat by a compression spring 31. The end of a lever 32 acts on the adjustable stem 33 of this valve, to lift it from its seat against the action of the closing spring 31. The lever 32 is in turn operated by a second lever 34; which is acted on by the thrust rod 35 of a tubular thermostatic device 36, which may be of any standard construction. The thermostatic device 36 is conveniently located under the upper part of the hood 25, as is apparent from Figs. 1 and 2, and has its supporting end carried by a screw-plug 37 which is mounted in one of the end castings 26. In this way, the tubular thermostatic device 36 is subjected to conducted heat carried to it from the roll 11 by the casting 26 which rubs on such roll, and is also subjected to heat of radiation and convection from the surface of the roll 11 beneath the hood 25.

As the temperature of the roll 11 rises, the tubular portion of the thermostat 36 expands by reason of the heat it receives from such roll, and thus moves its thrust rod 35 to the right (Figs. 2 and 4) to permit the spring 31 to move the valve 30 toward closed position; which cuts down the supply of gas to the burner 21, and thus reduces the heating action. On the other hand, if the tempera-

ture of the roll 11 falls, there is contraction of the tubular portion of the thermostat 36, which moves the thrust rod 35 to the left (Figs. 2 and 4) to open the valve farther, and thus to admit more gas to the burner 21 and thereby to increase the heating action.

If desired, a thermometer 40 may be associated with the hood, for determining the temperature developed therein. To this end, it is convenient to mount the base of the thermometer 40 in the middle casting 26 which rubs on the roll 11, so that it receives heat fairly directly from such roll. In this way, the temperature developed may be observed, to enable the operator to adjust the stem 33 of the valve to get the desired temperature control of the valve.

I claim as my invention:

1. In a dry-wood bending machine, the combination of three bending rolls arranged to act on a strip of wood to bend it, means within one of said bending rolls for heating it, and a hood over said heated bending roll, said hood comprising a sheet-metal body spaced from said heated roller, and carrying members which bear on the surface of said heated roll and carry said sheet-metal body.

2. A dry-wood bending machine, comprising three bending rolls for bending a strip of wood, means for heating one of said rolls, a hood over said heated roll for retaining heat therein, and a thermostat mounted in said hood for automatically controlling the heating of said heated roll.

3. In a dry-wood bending machine, the combination of a heated roll, and a hood over said roll for conserving the heat thereof, said hood being carried and spaced from said roll by members at each end thereof curved to fit the surface of the roll and resting thereon.

4. In a dry-wood bending machine, the combination of a heated roll, and a hood over said roll for conserving the heat thereof, said hood being carried and spaced from said roll by members at each end thereof curved to fit the surface of the roll and resting thereon, portions of said members extending outside said hood by which said hood is positioned, and positioning means on which said extending portions are attached.

5. In a dry-wood bending machine, the combination of a heated roll adjustable in a plane, and a hood over said roll for conserving the heat thereof, said hood being carried and spaced from said roll by members curved to fit the surface thereof and resting thereon, said hood also being pivotally supported on an axis parallel to said roll and spaced from the plane of adjustability of said roll.

6. In a dry-wood bending machine, the combination of a heated roll adjustable in a plane, and a hood over said roll for conserving the heat thereof, said hood being carried and spaced from said roll by members curved

to fit the surface thereof over substantially half its circumference and resting thereon, said hood also being pivotally supported on an axis parallel to said roll and spaced from the plane of adjustability of said roll.

7. In a dry-wood bending machine, the combination of a heated roll adjustable in a plane, and a hood over said roll for conserving the heat thereof, said hood being carried and spaced from said roll by members curved to fit the surface thereof and resting thereon, said hood also being pivotally supported on an axis parallel to said roll and spaced from the plane of adjustability of said roll, and a thermostat in said hood for automatically controlling the heating of said roll.

In witness whereof, I, T. R. LIVINGSTON, have hereunto set my hand at Muncie, Indiana, this 5th day of September, A. D. one thousand nine hundred and twenty-eight.
